ANTENNA SYSTEM

Thomas M. Gluyas, Jr., Westmont, N. J., assignor
to Radio Corporation of America, a corporation
of Delaware

Application June 30, 1945, Serial No. 602,444

4 Claims. (Cl. 250—33)

1

This invention relates to antennas, and more particularly to systems operable selectively over more than one band of frequencies. Although it is possible to adjust the tuning of an antenna system to resonance at any desired frequency within practical limits, such adjustment is time-consuming and may require a high degree of engineering skill and the use of expensive instruments. Accordingly it has become usual practice to employ pre-tuned antenna assemblies, designed to operate at one pre-determined frequency or band, and requiring only ordinary mechanical skill for installation.

Such antennas will operate efficiently only at the frequency for which they are designed. If operation is required at some other frequency, a different antenna must be substituted.

It is the principal object of the instant invention to provide an improved type of antenna system which has the simplicity of installation of a pre-tuned system and yet may be arranged readily to operate with high efficiency at either of two pre-determined frequencies.

Another object of the invention is to provide an antenna system including non-adjustable tuning means, reversible in position to produce resonance at either of two frequencies.

The invention will be described with reference to the accompanying drawing, wherein:

Figure 1 is a schematic diagram of an antenna system embodying the present invention,

Figure 2 is a detail view of one of the elements of the system of Figure 1,

Figure 3 illustrates a modification of the element shown in Figure 2,

Figure 4 is a graph illustrating the characteristics of the system of Figure 1 with two different connections of the tuning means, and

Figure 5 is a sectional view of a modified impedance transformer which may be used in the practice of the invention.

In accordance with the present invention, the radiator system is designed to resonate by itself at a frequency substantially midway between the two frequencies at which the overall antenna system is to be operable. Referring to Figure 1, the illustrated radiator system comprises a dipole including the radiator elements 1 and 3. It is to be understood that a more complex radiator system, such as a plurality of spaced interconnected dipoles, could be used instead of the simple dipole of Figure 1 without altering in any way the practice of the present invention.

2

The terminals of the radiator system are secured, for example by bolt and nut connections 5 and 7, to an impedance transformer 9. The transformer 9 is an open transmission line, substantially one-quarter wavelength long at the resonant frequency of the radiator system, and consists of two sections of approximately equal length but of different characteristic impedances.

Referring to Figure 2, each conductor of the transformer 9 comprises two pieces 11 and 13 of conductive tubing, secured together at the point 15 by welding, brazing or the like, and flattened at their outer ends 17 and 19 respectively to form terminals adapted for cooperation with the bolts 10 and nuts 5 and 7 on the radiator terminals. The diameters of the members 11 and 13 are predetermined in accordance with the desired resonance characteristics of the overall antenna system, as will appear more clearly hereinafter.

The impedance transformer 9 is connected to a feed system including conventional coupling and transmission line means. In the system of Figure 1, a coaxial line 21 extends to a radio utilization device, not shown, and is provided at its upper 15 end with terminals 23 and 25 connected to its inner and outer conductors respectively. The terminals 23 and 25 include nut and bolt means 20 25 similar to those on the radiators 1 and 3, for connection with the ends 17 or 19 of the conductors of the transformer 9.

The final quarter wavelength section 27 of the coaxial line 21 is surrounded by a conductive sleeve or cage 29, connected at its lower end to the outer conductor of the line 21 by a conductive disk 31. This arrangement constitutes a so-called "bazooka," or line balance convertor, for coupling the unsymmetrical or unbalanced-to-ground line 21 to the balanced-to-ground circuit of the dipole 1, 3 and the transformer 9.

Insofar as the operation of the present invention is concerned, it may be assumed that a balanced line or other balanced-to-ground circuit is connected to the terminals 23 and 25. The impedance presented by this circuit across the terminals 23 and 25 is substantially resistive, and 40 is of a magnitude denoted herein as R_L . When the impedance presented by the radiator system 1, 3 through the transformer 9 to the terminals 23 and 25 is also resistive, and of the value R_L , 45 energy is transferred with the maximum efficiency between the utilization circuit and the radiator system.

In accordance with prior art practice, the

radiators 1 and 3 would be connected directly to the terminals 23 and 25, and would be designed to have an impedance R_L at resonance. The operation would be entirely satisfactory at the resonant frequency. But to obtain reasonably efficiency at any other frequency, it would be necessary to redesign the radiator to exhibit a resistive impedance R_L at that frequency. This would usually involve more than merely retuning the radiator system, because the resonant impedance of a given radiator tuned to one frequency may be higher or lower than that of the same radiator tuned to a different frequency.

In accordance with the instant invention, the radiator 1, 3 is designed to resonate at a frequency f_0 , substantially midway between two frequencies f_1 and f_2 at which efficient operation is desired. Its impedance at the frequency f_0 may be approximately R_L . At the lower frequency f_1 , the impedance of the radiator is R_1-jX_1 , where R_1 is somewhat less than R_L , and X_1 is the capacitive reactance of the radiator at the frequency f_1 . At the higher frequency f_2 , the radiator impedance is R_2+jX_2 . R_2 is somewhat greater than R_L , and X_2 is the inductive reactance. The magnitudes of X_1 and X_2 are approximately equal to each other.

The transformer 9 may be regarded as two cascade-connected lines, each substantially one eighth wavelength long and having different characteristic impedances, Z_1 for the part formed by the larger conductors 13, and Z_2 for the part formed by the smaller conductors 11.

The impedance looking into one end of a transmission line is

$$Z_{in} = \frac{Z_{out} + jZ_c \tan \rho}{Z_c + jZ_{out} \tan \rho} Z_c$$

where Z_{out} is the impedance connected to the other end of the line, Z_c is the characteristic impedance of the line, and ρ is the electrical length of the line. In the case of an eighth wavelength line,

$$\rho = \frac{2\pi}{8} = 45^\circ$$

and $\tan \rho = 1$. Thus

$$Z_{in} = \frac{Z_{out} + jZ_c}{Z_c + jZ_{out}} Z_c$$

In the case of two eighth wavelength lines connected in cascade, Z_{in} for the first line is Z_{out} for the second. With the lines connected as shown in Figure 1, the impedance at the terminals 23 and 25 is

$$Z_{in} = \frac{\frac{Z_a + jZ_1}{Z_1 + jZ_a} Z_1 + jZ_2}{Z_2 + j\frac{Z_a + jZ_1}{Z_1 + jZ_a} Z_1} Z_2$$

where Z_a is the impedance of the radiator system. At the lower frequency f_1 , Z_a is R_1-jX_1 . By proper choice of the impedances Z_1 and Z_2 , Z_{in} may be made substantially equal to R_L , at the frequency f_1 .

Referring to Figure 4, the impedance match at the terminals 23 and 25 under the conditions of Figure 1 is shown by the curve designated f_1 of the standing wave ratio on the line 21. This is unity at the frequency f_1 , showing that no reflection and hence optimum transfer of energy occurs at that frequency.

Now let the transformer 9 be reversed, with the high impedance section connected to the

radiators. The impedance at the points 23 and 25 is

$$Z'_{in} = \frac{\frac{Z_a + jZ_2}{Z_2 + jZ_a} Z_1 + jZ_1}{Z_1 + j\frac{Z_a + jZ_2}{Z_2 + jZ_a} Z_2} Z_2$$

At the frequency f_2 , the radiator impedance Z_a is R_2+jX_2 . With the characteristic impedances Z_1 and Z_2 the same as before, it is found that Z'_{in} is substantially equal to R_L , at the frequency f_2 . The corresponding curve of standing wave ratio vs. frequency (Figure 4) shows optimum transfer at the frequency f_2 .

Thus the described antenna system provides equal and maximum efficiencies of operation at either of two predetermined frequencies, by simply interchanging the connections of a line impedance transformer between the radiators and the feed system. Although the invention has been described with reference to the use of a transformer of the stepped-line type, it will be apparent without further detailed explanation that a smoothly tapered line may be used instead. The word tapered is used in the appended claims to mean tapered by steps, as well as smoothly tapered. Referring to Figure 3, tapered conductors, each comprising a conductor continuously varying in diameter throughout its length, may be substituted for the stepped conductors in the transformer 9 of Figure 1.

Moreover, the practice of the invention is not limited to the use of open-wire line transformers, but may be embodied equally well in a system using unbalanced line sections for impedance transformation. Figure 5 illustrates a transformer of this type, comprising an outer conductor 35 of uniform diameter and an inner conductor including two sections 37 and 39 of different diameters. This structure may be used exactly like the transformer 9 of Figure 1 to provide an impedance match at either of two frequencies between an antenna and its feed system.

45 I claim as my invention:

1. An antenna system including naturally self-resonant radiator means, transmission means to be coupled to a utilization circuit, impedance transformer means comprising a transmission line section substantially one-quarter wavelength long at the resonant frequency of said radiator means, the conductors of said line section having one ratio of spacing to diameter at one end and a different ratio of spacing to diameter at the 50 other end, whereby said line section exhibits a relatively high characteristic impedance at one end and a relatively low characteristic impedance at the other end, and means for connecting said low impedance end to said radiator means and said high impedance end to said transmission means for operation of said system at one frequency and for connecting said low impedance end to said transmission means and said high impedance end to said radiator means for operation of said system at another frequency.

2. An antenna system for selective operation at either of two different frequencies, comprising radiator means naturally self-resonant at a frequency substantially midway between said two frequencies, whereby said radiator means exhibits a capacitive reactance at one of said two frequencies and a substantially equal inductive reactance at the other of said two frequencies, means for coupling said antenna system to a utilization circuit, impedance transformer means

comprising a quarter wavelength tapered transmission line section, and means for connecting said line section with its taper in one direction for operation at one of said frequencies and with its taper in the other direction for operation at the other of said frequencies.

3. A multi-band antenna system including radiator means naturally resonant at a frequency substantially midway between the center frequencies of two frequency bands through which the system is to operate, an impedance transformer comprising a quarter wavelength line consisting of at least two cascaded sections having different characteristic impedances, means for connecting a utilization device to said radiator means in one direction through said quarter wave line section for operation in one of said bands, and means for connecting a utilization device in the other direction through said quarter wave line for operation in the other of said bands. 10

4. In combination with a circuit element self-resonant at a frequency f_0 and a utilization circuit to be coupled to said element, a reversible transformer section connected between said element and said utilization circuit and comprising 25

a quarter wavelength tapered transmission line section and means for connecting said line section with its taper in one direction for operation at one frequency greater than f_0 and means for connecting said line section with its taper in the other direction for operation at a different frequency less than f_0 .
